UNITED STATES PATENT OFFICE.

SALVATORE F. BILOTTI AND JUANITA H. LEONARD, OF NEW YORK, N. Y.

DESIGN FOR A CANDLE.

Application filed March 1, 1924. Serial No. 8,790. Term of patent 7 years.

To all whom it may concern:

Be it known that we, SALVATORE F. BILOTTI and JUANITA H. LEONARD, citizens of the United States of America, residing at New York, county of New York, and State of New York, have invented a new, original, and ornamental Design for Candles, of which the following is a specification, reference being had to the accompanying drawing, forming part thereof.

We claim:

The ornamental design for a candle as shown.

SALVATORE F. BILOTTI.
JUANITA H. LEONARD.
